UNITED STATES PATENT OFFICE

153,669

DESIGN FOR A HANDBAG FRAME

Louis S. David, New York, N. Y.

Application May 1, 1948, Serial No. 146,120

Term of patent 3½ years

(Cl. D87—2)

To all whom it may concern:

Be it known that I, Louis S. David, a citizen of the United States of America, residing in New York city, county of New York, and State of New York, have invented a new, original, and ornamental Design for a Handbag Frame, of which the following is a specification, reference being had to the accompanying drawing, forming part thereof, wherein:

The rear of the handbag frame is identical in appearance to the front shown.

I claim:

The ornamental design for a handbag frame, substantially as shown and described.

LOUIS S. DAVID.
